Primary Examiner — Elizabeth Albert(74) *Attorney, Agent, or Firm* — J. Douglas Wells**CLAIM**

The ornamental design for a tray, as shown and described.

DESCRIPTION

FIG. 1 is a top perspective view of a tray showing my new design;

FIG. 2 is a bottom perspective view of the tray shown in FIG. 1;

FIG. 3 is a front elevation view of the tray shown in FIG. 1; FIG. 4 is a right side view of the tray shown in FIG. 1; FIG. 5 is a rear elevation view of the tray shown in FIG. 1; FIG. 6 is a left side rear elevation view of the tray shown in FIG. 1;

FIG. 7 is a top plan view of the tray shown in FIG. 1; and, FIG. 8 is a bottom plan view of the tray shown in FIG. 1. The broken lines shown in the drawings represent portions of the tray that form no part of the claimed design.

1 Claim, 6 Drawing Sheets(56)
